Primary Examiner — Barbara Fox(74) *Attorney, Agent, or Firm* — Staas & Halsey LLP(57) **CLAIM**

The ornamental design for a terminal for portable mobile communication, as shown and described.

DESCRIPTION

FIG. 1 is a front perspective view of terminal for portable mobile communication;

FIG. 2 is a front view of the terminal for portable mobile communication of FIG. 1;

FIG. 3 is a rear view of the terminal for portable mobile communication of FIG. 1;

FIG. 4 is a left-side view of the terminal for portable mobile communication of FIG. 1;

FIG. 5 is a right-side view of the terminal for portable mobile communication of FIG. 1;

FIG. 6 is a top plan view of the terminal for portable mobile communication of FIG. 1; and,

FIG. 7 is a bottom plan view of the terminal for portable mobile communication of FIG. 1.
